UNITED STATES PATENT OFFICE.

SALUSTIANO B. GARCELLANO, OF CHARLESTON, SOUTH CAROLINA.

BREAK RELAY FOR RADIO RECEIVING-SENDING SETS.

Application filed November 7, 1924. Serial No. 748,424.

To all whom it may concern:

Be it known that I, SALUSTIANO B. GARCELLANO, a citizen of the Philippine Islands, residing at Charleston, in the county of Charleston and State of South Carolina, have invented certain new and useful Improvements in a Break Relay for Radio Receiving-Sending Sets, of which the following is a specification.

10 This invention relates to improvements in radio receiving and sending sets, and particularly to a break relay adapted to be interposed in the antenna circuit, and operable for controlling the circuit.

15 An object of the invention resides in providing a device by which the signals may be periodically broadcast, in the usual manner, and in the sending operation will connect the sending circuits for broadcasting 20 the signal, with the antenna circuit, and will simultaneously short circuit a receiving set or circuit connected with the antenna, which is operable between the sending of the impulses, for receiving signals over the same 25 antenna.

Another object of the invention is to combine a sending and receiving set, so that the same may be used with a single antenna circuit, wherein means is provided for short 30 circuiting the receiving set, during the sending of a signal by the sending circuit or set, but which is fully operable during the interval between the sending of signals.

A further object of the invention is to 35 provide a device, for controlling the antenna circuit adapted for common use, with the sending and receiving set, which not only operates to control the antenna circuit, so as to cut out the receiving set, during the 40 operation of the sending set, but which also operates to energize the sending circuit, for sending the signal impulse.

Other objects and improvements in the 45 details of construction and arrangement of parts, are more particularly pointed out, in the following detailed description and claim, directed to a preferred form of the invention, it being understood that various other constructions and methods of carrying 50 out the desired result, may be obtained, that are within the scope of this invention, and without departing from the scope of the appended claim.

In the drawing, forming a part of this 55 application:

The figure illustrates a diagrammatic

view, showing the manner of using a solenoid operated switch, forming the subject matter of this invention, for controlling the operation of a sending set, and an antenna 60 circuit common to both a sending and receiving set.

1 indicates the antenna, which is connected with the usual antenna inductance 2, which in turn is connected to one terminal of the secondary 3 of the sending transformer. The other terminal of the secondary of the sending transformer is connected to the ammeter 4, from which extends a wire 5, making electrical connection with the ground 6 under conditions, which will be presently described. The primary of the sending transformer is indicated at 7, which is connected in circuit with a step-up transformer 8, a quenched gap 9, and a condenser 10, which parts are merely shown to indicate a portion of the sending circuit of usual and well known type.

An electromagnet, forming a part of the structure of the present invention, is indicated at 11, which includes a pair of serially connected coils 12, having a movable core 13 connected together at their free ends by a bridge piece 14, forming a movable armature which carries a projecting arm 15, on the free end of which is pivotally mounted a breaker arm 16, carrying at its ends, contact point 17 and 18, respectively, which are adapted for engagement with contacts 19 and 20, respectively, carried by a stationary arm 21. The breaker arm 16 has a limited pivotal movement on the end of the arm 15, limited by the stop 22, while a coil spring 23, normally under compression, is positioned between the breaker arm 16 and the contact arm 21, for normally retaining the breaker arm against the stop 22, for a purpose which will presently appear. The contacts 18 and 20, are connected in the respective sides of the circuit of the primary of the step-up transformer 8, while a wire 5 of the antenna circuit is connected to the contact 17, and a wire 24 connects the contact 19, with the ground 6, so that when said contacts 17 and 19 are engaged, the antenna circuit will be completed to the ground, for the operation of the sending set, and the sending of a signal thereby, in a manner which will be described.

A battery is indicated at 25, and a sending key at 26, which is connected in circuit with the battery and the coils 12 of the

electromagnet, forming a breaker arm operating circuit, as well as a sending signal control circuit.

When it is desired to send a signal, using the circuits, as above described, the depression of the key 26 will energize its circuit, and the coils 12 of the electromagnet, which are operable, for projecting the cores 13 and the cross arm 14 from the coils 12, 10 to move the breaker arm 16, toward the contact arm 21, in such a manner that the contacts 17 and 19 will first contact, followed by the contact between the contact points 18 and 20, due to a relative pivotal 15 movement of the breaker arm, on the arm 15, which will cause the circuit from the primary 8 of the sending set-up transformer, and energize and operate the sending circuit for the sending of a signal 20 impulse, in the usual and well known manner. A receiving circuit is indicated generally at 27, and the receiving transformer 28 thereof has the primary 29 connected by the wires 30 and 31, to the contacts 19 and 17 25 respectively.

During the interval between the sending of signal impulses, the contacts 17 and 19, and 18 and 20 respectively, are held disconnected, or in open relation, as illustrated in the drawing, through the medium of the compression spring 23, at which time, the wires 30 and 31 make a circuit through the primary 29, with the antenna and the ground, so that the antenna used in sending signal impulses, is used between impulses, for the receiving of signals by the receiving set 27, in a manner which should be readily appreciated by an inspection of the drawing. Upon the energization of the 30 coils 12 for the sending of the signal, which operates, as above described, to close the contacts 17 and 19, and 18 and 20, respectively, it will be seen that by having the limited pivotal movement of the breaker 40 arm 16, the contacts 17 and 19 having electrical contact prior to the engagement of contacts 18 and 20 will short circuit the connections 30 and 31, and the primary of the receiving transformer 28, so that the 45 subsequent sending of the signal by the engagement of the contacts 18 and 20, and the energization of the antenna and ground circuits will not act to affect the receiving set, or to impress heavy currents in the primary thereof, due to the short circuiting of the receiving circuit prior to the making of the sending circuit. In this 55 way, the receiving circuit is at all times protected against injury through the heavy 60 currents used in sending signals, while during the intermission between the sending of signal impulses, the receiving set is con-

stantly operable, for utilizing the antenna circuit for the receiving of signals. It should thus be appreciated that a means 65 has been provided for controlling the operation of the sending set, and also the antenna circuit, so that a common antenna circuit may be used, for both a sending and receiving set.

A substantial improvement is therefore provided in the art, which is particularly useful aboard ships, or in other places where sending and receiving sets for radio signals are used, and where the amount of space 75 for the mounting of aerials, is substantially limited, and which efficiently controls both the sending and receiving circuits, to prevent damage to either, and effectively controls the sending of the signals, by the sending set.

Having thus described my invention, what is claimed is:

A device of the class described, comprising an energizable coil, a movable core 85 mounted in said coil for axial movement therethrough in accordance with the energization of the coil, a bar member connected with and projecting from said core, a breaker arm having its central portion pivotally mounted on the end of said bar member, means on said breaker arm for engagement with said bar member for limiting the pivotal movement in one direction of the breaker arm on said bar member, a pair of contact members carried in the free end of said breaker member, a stationary contact member having a pair of contacts at the end portions thereof insulated from one another, resilient means positioned between said breaker member and said stationary contact member normally 90 operative to hold said breaker member at one limit of its pivotal movement, manually controlled means for energizing said electrical coil adapted to operate said core for moving the breaker member toward said stationary contact member, the contact at one end of said breaker arm being adapted for engagement with the corresponding contact on the stationary contact member before engagement of the contact at the opposite end of said member, said first mentioned contact being included in the antenna circuit and receiving the circuit, the last mentioned contacts being included in the sending circuits, whereby said coil will control the operation of the sending circuit and short circuit the receiving circuit at the same time closing the antenna circuit before 100 the operation of the sending circuit.

In testimony whereof I affix my signature.

SALUSTIANO B. GARCELLANO.
